WINDING DEVICE FOR STRAND MATERIALS

William V. Henry, Candler, N. C., assignor to
American Enka Corporation, Enka, N. C., a corporation of Delaware

Application August 24, 1942, Serial No. 455,921

6 Claims. (Cl. 242—46.2)

This invention relates to winding spools and more particularly to an improved spool and spindle assembly for use in winding strand material.

The present invention is particularly adapted to the type of spool generally employed in rewinding textile yarn. Such a spool is mounted upon a spindle and connected thereto for rotation therewith, and upon completion of winding, the filled spool is removed and placed on another textile machine for rewinding into a form suitable for use by fabric manufacturers. On the winding machine, the ends of the spindle projecting from each end of the spool are mounted for rotation in bearings affixed to the winding machine, and the spool is rotated by means of a driven pulley affixed to the spindle adjacent one of the spool ends. It is obvious, of course, that the connection between spool and spindle should be sufficiently tight to prevent vibration and slippage during operation, and should likewise be of such a nature that spool and spindle may be easily and quickly separated, so that a filled spool may be replaced with an empty one and the winding operation continued without unnecessary delay.

An object of the invention, therefore, is the provision of an improved winding device, wherein a tight connection is maintained between the spool and spindle.

Another object is the provision of an improved spool and spindle assembly of simple construction whereby a filled spool may be quickly and easily removed and replaced with an empty spool.

A further object is the provision of an improved spool and spindle wherein the spindle is held in frictional engagement with the spool.

Other objects and advantages will appear from a consideration of the following specification when read in conjunction with the annexed drawing wherein

Figure 1 is an elevation, partially in section, of my improved spool and spindle assembly, showing the spindle partly inserted in the spool.

Figure 2 is a view similar to Figure 1 showing the spindle in operative engagement with the spool, and showing the driving arrangement.

Figure 3 is a section taken along the line 3—3 of Figure 1.

Figure 4 is an elevation, partially in section, showing a modified form of spool and spindle assembly according to my invention, and

Figure 5 shows the same modification in operative engagement with the spool.

Referring to Figure 1, the spool customarily

utilized in practicing the present invention comprises a cylindrical body portion 1 having heads 2 and 3 affixed to the ends thereof. The spool is provided with a central bore 4 extending longitudinally thereof adapted to receive a spindle 5, which, when fully inserted therein, projects from the spool at both ends.

Affixed to spindle 5 near one end thereof is a pulley 6 preferably made of wood and having a beveled face 7. Pulley 6 is provided for a portion of its length with an outer layer of cork or the like 8 to provide a suitable contact surface for the driving mechanism by which the pulley is rotated. Likewise affixed to spindle 5 adjacent 10 the beveled face of pulley 6 is a resilient metal strip or spring key 9 adapted for insertion in an annular recess 10 in spool head 2 concentric with central bore 4. Recess 10 is flared so that its inner diameter is greater than the outer diameter thereof, and its rear wall is concave and extends into the body of the spool. Also concentric with bore 4 is a counterbore 11 of lesser diameter than the recess, and adapted to receive a hub 12 affixed to spindle 5 adjacent pulley 6. 15 The length of spring key 9 is slightly greater than the inner diameter of annular recess 10, but is bent slightly in the direction of the spool so that, upon insertion of spindle 5 in bore 4 spring key 9 will pass through the mouth of the said recess. The side 7 of pulley 6 is beveled to conform to the shape of the concave rear wall or recess 10, and upon exerting pressure upon the spindle end adjacent the pulley, spring key 9 will spread until the edges thereof contact the inner periphery of recess 10 and its face will contact the concave rear wall of the recess. Simultaneously hub 12 is inserted in counterbore 11. It is obvious, of course, that counterbore 11 and hub 12 may be eliminated, if desired, without seriously impairing the rigidity of the winding assembly. The assembled spool and spindle and the means for rotating the same are shown in Figure 2. The spindle ends rest in bearings 13 and 14, bearing 13 being open at the top to facilitate placement and removal of spools. Pulley 6 is rotated by contact with a wheel 15 mounted on a shaft 16 and driven from any suitable source of power, not shown.

In the modification shown in Figures 4 and 5 the function of recess 10, shown in Figures 1 and 2, is served by an annular concave dish-like member 17 affixed to head 18 of a spool 19 by means of screws or bolts 20. Spool 19 is provided with a central bore 21 adapted to receive a spindle 22, having affixed adjacent one end thereof a pulley

23 and a spring key 24. The spindle, pulley and spring key assembly shown in Figures 4 and 5 is similar in every respect to that shown in Figures 1 and 2 except that counterbore 11 and hub 12 are eliminated.

It should be understood that a slight pressure exerted upon the end of the spindle adjacent the pulley will force the spring key into locked position in annular recess 10 or concave member 17, and that a slight pressure against the opposite end of the spindle will be sufficient to sever the connection between the spool and spindle and permit easy replacement of the spool.

It should be further understood that modifications may be made in the present invention without departing from the spirit thereof. Therefore, my invention should be limited only by the scope of the appended claims.

What is claimed is:

1. A collecting device for strand material comprising a spool, an annular receiving means having a concave inner wall associated with one end only, of said spool concentric with the axis thereof, a spindle, and a radially projecting metallic spring key affixed to said spindle, said spring key being normally urged in the axial direction of the spool and arranged for frictional engagement with the inner wall of said annular receiving means.

2. A collecting device for strand material comprising a spool, a spindle extending therethrough, a driven pulley affixed to the spindle exteriorly of the spool, an annular receptacle associated with one end of said spool and concentric with said spindle, and a radially projecting, metallic spring key affixed to said spindle, said spring key being normally urged in the axial direction of the spool and arranged for frictional locking engagement with a wall of said annular receptacle.

3. A collecting device for strand material comprising a spool, a spindle extending therethrough, a driven pulley affixed to the spindle exteriorly of the spool, a flared annular recess concentric with said spindle and having a concave rear wall in one end of said spool, and a metallic spring key affixed to and extending radially from said spindle adjacent the inner end of said pulley, said spring key being normally urged in the axial di-

rection of the spool and arranged for frictional locking engagement with the walls of the annular recess.

4. A collecting device for strand material comprising a spool, a spindle extending therethrough, a driven pulley affixed to the spindle exteriorly of the spool, a flared annular receptacle affixed to one end of said spool concentric with said spindle and having a concave rear wall, and a metallic spring key affixed to and extending radially from said spindle adjacent the inner end of said pulley, said spring key being normally biased in the axial direction of the spool and arranged for frictional locking engagement with the walls of the annular receptacle.

5. A collecting device for strand material comprising a spool having a central bore extending longitudinally thereof, a spindle extending therethrough, a driven pulley affixed to the spindle exteriorly of the spool, one end of said spool being provided with a tapering annular receptacle concentric with said bore, and a beveled, metallic spring key affixed to and extending radially from said spindle adjacent the inner end of said pulley, said spring key being normally biased in the axial direction of the spool and arranged for frictional engagement with the walls of the tapered receptacle.

6. A collecting device for strand material comprising a spool having a central bore extending longitudinally thereof, a spindle extending therethrough, a driven pulley affixed to the spindle exteriorly of the spool, bearings for the spindle adjacent the remote ends of the pulley and spool, one end of said spool being provided with a tapering annular recess concentric with said bore and terminating in a counterbore, a metallic spring key affixed to and extending radially from said spindle adjacent the inner end of said pulley and a hub mounted on the spindle adjacent said spring key, said spring key being normally biased in the axial direction of the spool and arranged for frictional engagement with the walls of the tapered recess when the spindle with the spool thereon is mounted in said bearings, said hub being retained in said counterbore.

WILLIAM V. HENRY.
